PAIR OF SPECTACLES

Alexander A. Kono, Jr., Lake Success, N. Y.

Application June 4, 1954, Serial No. 30,806

Term of patent 3½ years

(Cl. D57—1)

Fig. 1 is a front elevational view of a pair of spectacles showing my new design;

Fig. 2 is a top plan view thereof; and

Fig. 3 is a side elevational view thereof taken from the right side of Fig. 1.

The dominant features of my design reside in the portions shown in full lines.

I claim:

The ornamental design for a pair of spectacles, substantially as shown and described.
